UNITED STATES PATENT OFFICE.

CHARLES C. CROSSLEY, OF PORT CHESTER, NEW YORK.

COLLAPSIBLE CORE.

957,599.

Specification of Letters Patent. Patented May 10, 1910.

Application filed November 12, 1907. Serial No. 401,808.

To all whom it may concern:

Be it known that I, CHARLES C. CROSSLEY, a citizen of the United States, residing at Port Chester, county of Westchester, and 5 State of New York, have invented a certain new and useful Improvement in Collapsible Cores, of which the following is a specification.

My invention relates to a new and useful 10 improvement in expansion tubes or cores for constructing concrete or cement walls or building blocks, and has for its object to provide an exceedingly simple and effective device by the use of which the air spaces in 15 concrete walls or building blocks may be readily formed and from which the tube may be readily withdrawn by first being contracted so as to avoid marring the space which it has formed.

20 With these ends in view, this invention consists in the details of construction and combination of elements hereinafter set forth and then specifically designated by the claims.

25 In order that those skilled in the art to which this invention appertains may understand how to make and use the same I will describe its construction in detail, referring by letter to the accompanying drawing 30 forming a part of this specification, in which—

Figure 1 is a vertical section, a portion of which is broken away to show that the tube may be of any desired length. Fig. 2, a section at the line X—X of Fig. 1. Fig. 3, a 35 vertical section taken at the line Y—Y of Fig. 2. Fig. 4, plan view of the two halves of which the tube is composed. Fig. 5, is a broken away view of the top showing one of 40 the elongated slots for the screws which hold the cap in place.

In carrying out my invention as here embodied, A represents the casing which is composed of the two sections a, each section 45 having two webs B which run diagonally across the sections, one near the top and the other near the bottom, and each of these webs are flanged, and when the two sections are together these flanges overlap each other 50 as clearly shown in Fig. 3 so as to hold the sections together. The sections of the casing when assembled overlap each other at their edges as clearly shown in Fig. 2, thus permitting a contracting movement diagonally, that is to say, when the sections are 55 drawn toward each other their overlapping

edges will cause them to move at an angle to the axis of the width of the casing, whereby the casing will be contracted in all directions so as to permit it to be withdrawn from the 60 space for which it was used as a core. To bring about this contraction of the sections of the casing I provide a central shaft or rod C which is provided with the incline front lug D and rear lug D' at the upper 65 and lower end thereof, and these lugs fit in the slots E formed in the webs so that when the rod is forced in one direction the sections of the casing will be expanded, and when forced in the opposite direction the 70 sections will be contracted. The expansion of these sections is accomplished as follows:— When the rod C is moved upward the lugs D and D' being inclined toward their tops from side to side will cause the tube to expand from side to side, at the same time the incline surface D² of the lugs D and incline surface D³ of lugs D' will cause the tube to 75 expand from end to end.

F represents the cap which is fitted over 80 the sections and is held thereto by the screws G which pass through elongated slots in the cap so as to provide for the movement necessary for the expansion and contraction of the sections, and in the center of this cap 85 is fitted the operating screw H which is threaded into the rod C as clearly shown in Fig. 1, and this operating screw has formed therewith the handle I by which it is revolved, and the revolving of this screw will 90 raise or lower the rod C as the screw is turned in one direction or the other.

From the foregoing description it will be seen that my improved core when expanded may set in a mold and when the cement or 95 concrete has been molded around the same and set the tube may be contracted as before described sufficiently to free it from the molded mass and permit its ready removal from the space thus formed. This is 100 of great advantage in that when solid cores are used they adhere more or less to the mass molded around them and are often removed with great difficulty and in many cases with injury to the walls or blocks, but 105 these disadvantages are entirely overcome by my improved core tube as above described.

Of course I do not wish to be limited to the exact details of construction here shown as these may be varied within certain 110 limits without departing from the spirit of my invention.

Having thus fully described my invention, what I claim as new and useful, is—

1. In a device of the character described, two sections adapted to fit together so as 5 to form an oblong core, webs carried by said sections, flanges formed upon said webs, said flanges overlapping each other, a central rod, wedge-shaped lugs formed upon said rod, said lugs fitting within slots formed 10 in the webs whereby the sections may be expanded or contracted, and an operating screw for bringing about the movements of the rod, as specified.
2. In a device of the character described, 15 two sections adapted to fit together so as to form an oblong core, webs carried by said sections, flanges formed upon said webs, said flanges overlapping each other, a central rod, wedge-shaped lugs formed upon said rod, 20 said lugs fitting within slots formed in the webs whereby the section may be expanded or contracted, an operating screw for bringing about the movements of the rod, and

a cap in which said operating screw is fitted to turn, as specified.

25

3. In a device of the character described, two sections adapted to fit together so as to form an oblong core, webs carried by said sections, flanges formed on said webs, said flanges overlapping each other, a central 30 rod, wedge-shaped lugs formed upon said rod, said lugs fitting within slots formed in the webs whereby the sections may be expanded or contracted, an operating screw for bringing about the movements of the 35 rod, a cap in which said operating screw is fitted to turn, and a handle secured to the operating screw for manipulating the same, as specified.

In testimony whereof, I have hereunto 40 affixed my signature in the presence of two subscribing witnesses.

CHARLES C. CROSSLEY.
